(57) **CLAIM**

The ornamental design for a cap with hinged lid, write-on surface and writing implement holder, as shown and described.

DESCRIPTION

FIG. 1 depicts a perspective view of a cap showing my new design with a hinged lid in one open position.

FIG. 2 depicts a front view of the cap of FIG. 1.

FIG. 3 depicts a rear view of the cap in FIG. 1.

FIG. 4 depicts a right view of the cap in FIG. 1.

FIG. 5 depicts a left side view of the cap in FIG. 1.

FIG. 6 depicts a top view of the cap in FIG. 1.

FIG. 7 depicts a bottom view of the cap in FIG. 1.

FIG. 8 depicts another perspective view of the cap in FIG. 1 with the hinged lid in a closed position.

FIG. 9 is a front view of the cap of FIG. 8.

FIG. 10 depicts a top view of the cap in FIG. 8.

FIG. 11 depicts a front view of the cap of FIG. 1 with the hinged lid in one open position.

FIG. 12 depicts a front view of the cap of FIG. 1 with the hinged lid in one open position.

FIG. 13 depicts a front view of the cap of FIG. 1 with the hinged lid in one open position; and,

FIG. 14 depicts an exploded perspective view of the cap in FIG. 1 in an environment of use.

In the drawings, the broken lines depict environmental elements of the cap and form no part of the claim.
